UNITED STATES PATENT OFFICE.

ELMER E. POOLE, OF BOSTON, MASSACHUSETTS.

COMBINATION TAIL-LIGHT, SIGN-PLATE, AND HOLDER THEREFOR FOR VEHICLES.

1,087,548.

Specification of Letters Patent. Patented Feb. 17, 1914.

Application filed April 2, 1912. Serial No. 687,996.

To all whom it may concern:

Be it known that I, ELMER E. POOLE, citizen of the United States, residing at Boston, county of Suffolk, State of Massachusetts, have invented a certain new and useful Improvement in Combination Tail-Lights, Sign-Plates, and Holders Therefor for Vehicles, of which the following is a specification, reference being had therein to the accompanying drawings.

In most, if not at all of the States there are laws requiring motor vehicles to carry a sign plate bearing the license number which must be at all times carried at the end 15 of the vehicle, usually at the rear of an automobile and at night there must also be a tail light. There are various laws, rules and regulations in the various States of the United States relating to the display of the 20 sign plate and the object of the present invention is to provide a simple and effective device to cover various contingencies in the matter of displaying the license number and to combine the sign plate and tail light in a 25 single fixture so that the number can be easily read by night, as well as by day. The sign plates furnished by at least some of the States are made of metal so that the license 30 number on the sign plate is not readily distinguishable at night even when there is a bull's eye or tail light carried adjacent to the sign plate.

The invention will be fully understood from the following description taken in 35 connection with the accompanying drawings, and the novel features will be pointed out and clearly defined in the claims at the close of the specification.

In the drawings,—Figure 1 is a perspective view of a device embodying the invention. Fig. 2 is a front elevation of the box shown in Fig. 1, the front turned up on its hinge. Fig. 3 is a section on line 3—3 of Fig. 1.

Referring now to the drawings:—In describing the device that side of the box which is exposed when looking toward the device when it is attached to the vehicle will be referred to as the front of the box. 45 The box may be of any suitable material, preferably metal. The body 1 of the box is preferably of oblong shape about the right size to receive the oblong sign plate. The front side 2 is hinged to the body of the box, preferably so as to open upward. The sign 50 plate 4 is placed in the back part of the box

being held in place by suitable means, as by a lip 11 rising from the bottom of the box and by suitable clips, such for instance as the clips 3, shown in the drawings, which 55 may be bent over the edge of the plate 4. This sign plate 4 may be the regular sign plate issued by the authorities that grant the license, this usually being furnished by the State and is usually of metal. Usually the 60 sign plate thus issued is of a particular color and the figures thereon are of a particular contrasting color.

The front of the box is composed of a frame 2 and a translucent glass sign plate 5 65 detachably connected therewith. The coloring, figures and lettering on this glass plate should be a copy of that on the metal sign or license number plate 4 within the box, so that when said hinged front is closed the 70 exposed glass plate will show exactly the same marking and coloring as the regular sign plate within the box would show if it were exposed. Suitable holding means are provided whereby the said glass or translucent plate 5 may be readily detached and 75 replaced by another plate when desired. The means shown in the drawings are clips 6 of flexible metal which can be easily bent to remove the sign and admit a new one and 80 then bent back again to hold the new plate 85 in place.

The body of the box has a downwardly extending portion 7 preferably extending 80 downwardly from the middle of the lower side of the box to receive a lamp 8 suitably mounted therein, and the front frame 2 has a corresponding downwardly extending portion 9 which shuts over the downwardly 85 extending body portion 7. A bull's eye 10 of suitable colored glass or other translucent 90 material is set into this said downwardly extending portion 9 of the front frame, and will be illuminated by the lamp 8 when the lamp is lighted at night. As the metal sign 95 plate 4 is held in the back part of the box, the interior of the box will be illuminated and the number can be easily read at a distance. If for any reason the translucent glass plate is broken and entirely removed, 100 the metal sign plate in the rear of the box will be exposed so that two sign plates are really afforded, one for ordinary use and the other for use in an emergency. In case of 105 breakage of the front glass plate the rear plate could be placed in the front part of 110 the frame from which the glass plate was

removed but preferably it would be retained in the back part of the box because while it remains in the back part of the box it will be illuminated by the lamp below and in 5 front of it although not so plainly visible at night as the translucent glass plate.

What I claim is:—

1. A combination tail light, sign plate and holder comprising a case having a translucent sign plate which in itself forms part of the front of said case, a sign plate on which the legible matter is a copy of that on said translucent plate mounted in the interior of the box at some distance behind said translucent plate, leaving a chamber free from obstruction between said two plates, and so arranged that when said front plate is removed the said rear plate is fully exposed to front view without change of position, and 15 an illuminating device in the interior of the box out of alinement with said sign plates and which is adapted to illuminate said translucent sign plate.
2. A combination tail light, sign plate and holder comprising a case having a translucent sign plate which forms a part of the front of said case, a sign plate on which the legible matter is a copy of that on said translucent plate mounted in the interior of 25 the box at some distance behind said translucent plate, leaving a chamber free from obstruction between said two plates, and so arranged that when said front plate is removed the said rear plate is fully exposed 30 to front view without change of position, a chambered extension to the body of the box, an illuminating device mounted in said extension, an extension to the front wall of the box having a translucent bull's eye inserted 35 40 therein in front of the said extension of the box whereby said illuminating means illuminates both the bull's eye and the translucent sign plate, and also illuminates the said rear plate.
3. A combination tail light, sign plate and holder comprising a box having the front thereof hinged to the body portion, a sign plate mounted in the rear part of the body of the box, a translucent sign plate on 45 50 which there is a copy of the legible matter of said first plate and which forms a part of

the front of the box spaced at some distance in front of said first sign plate, the space between said two sign plates being entirely free from obstruction, the body of the box 55 having an extended portion, an illuminating means located in said extension, said front portion having also an extension corresponding with the extension of the body of the box, a translucent bull's eye mounted in said 60 front extension whereby said illuminating means illuminates both the bull's eye and the translucent sign plate from the rear thereof, and also illuminates the front of said rear sign plate without change of position, where- 65 by it is visible both at night and by day when the front sign plate is removed.

4. A combination tail light, sign plate, and holder comprising a case having a sign plate in the rear part thereof, facing toward the 70 front of the case, a front hinged to the upper front side of the body of the case and normally being turned down to close the front of the case, a translucent sign plate on which there is a copy of the legible matter 75 of said rear plate and which forms a part of said hinged front of the case, the space between said translucent front and said rear sign plate being entirely unobstructed, so that if the front sign plate is removed the 80 rear sign plate will be fully exposed to view, the lower part of the body of said case being formed with a downwardly extending portion which opens into the space in said body portion between said front and said 85 rear sign plate, the said front portion being also formed with a downwardly extending portion directly in front alinement with said downwardly extending portion of the body, a bull's eye mounted in said downwardly ex- 90 tending portion of the front, and a lamp mounted in said downwardly extending body portion, so arranged that the rays from said lamp illuminate the front of said rear sign plate and the rear of said front 95 plate.

In testimony whereof I affix my signature, in presence of two witnesses.

ELMER E. POOLE.
